RADIO RECEIVING SYSTEM

Harry J. Nichols, Dayton, Ohio, Henry C. Forbes, Anderson, Ind., Walter S. Harmon, Chicago, Ill., and Homer J. Loftis, Ironton, Ohio, assignors, by mesne assignments, to Radio Corporation of America, New York, N. Y., a corporation of Delaware

Application September 21, 1932, Serial No. 634,138

1 Claim. (Cl. 250—20)

This invention relates to a radio receiving system and is particularly adapted to a remotely controlled radio receiving device.

An object of this invention is to provide a selective unit for use with a radio wave translating device that may be flexibly attached to said device and control the device in accordance with the desires of an operator.

Another object of this invention is to provide a control unit for a radio receiver which receives its operating potentials and currents from the radio receiver with which it is used.

Another object of this invention is to provide a means for controlling the volume output of a radio receiving system by controlling the voltage of the signal energy between the signal frequency selecting unit and the amplifying unit.

Another object of this invention is to provide an improved means for mixing the signal energy with locally generated oscillations.

Another object of this invention is to provide a means for supplying the filament or cathode heating current for one or more tubes of a radio circuit by utilizing the normal operating current of one or more other tubes.

Further objects and advantages of the present invention will be apparent from the following description, reference being had to the accompanying drawing wherein a preferred embodiment of one form of the present invention is clearly shown.

In the drawing:

The single figure discloses a circuit of a remote controlled unit for a radio receiver, and indicates essential elements of the receiver or amplifier to which the control unit is connected.

With particular reference to the drawing, a primary inductance 10 is connected in series with an antenna 1 and a ground 2. The primary inductance 10 is magnetically coupled to a secondary inductance 14 to form the coupling unit 12, and the grounded end of the primary inductance 10 is connected to one end of the secondary inductance 14. The other end of the secondary inductance 14 is connected to an input or control electrode 18 of a thermionic detector tube 20. A variable condenser 16 is connected to the ends of the secondary inductance 14 to form a tunable resonant circuit 25.

The detector tube 20 has, beside the input or control electrode 18, a filament or cathode element 22, a screen grid 24 and an anode or output electrode 26 therein. The screen grid 24 is connected to a tap 28 on a resistor 30. The extremities of the resistor 30 are connected to ground at 32 and to a lead 34. The lead 34 is

connected to a convenient point of a radio device from which a positive potential may be obtained of sufficient magnitude for the elements of the tubes to which it is connected. The anode or output electrode 26 is connected to the lead 34 through inductances 36 and 38 which are connected in series.

A condenser 40 connected between the screen grid 24 and one side of the filament 22, and a condenser 42 connected between the lead 34 and the same side of the filament circuit, form bypass circuits for any high frequency currents from the screen grid 24 and anode 26 respectively. The same side of the filament 22 that is connected to the condenser 40, is connected through a choke 44 and a resistance 46 to ground at 2. A condenser 48 has one side connected to a point intermediate the inductances 36 and 38, and its other side connected to a resistor 50, which has a variable tap 52 connected to a lead 56 of a cable, and an end connected to ground at 54. The same side of the filament 22 that connects to the condenser 40 and the choke 44 is connected to one side of a condenser 58, that is in turn connected to ground at 60 through an inductance 62. The other side of the filament 22 is connected to one side of a filament 64 of a thermionic oscillator tube 66.

The thermionic oscillator tube 66 has an anode 68 connected through an inductance 70 and a resistor 72 to the tap 52 on the resistor 30. A control electrode 74 of the thermionic tube 66 is connected through a resistance 76 to that side of the filament 64 that connects to the filament 22. The control electrode 74 is also connected to one end of an inductance 78. Condensers 80 and 82 are connected in series, and one end of the series combination is connected to an end of the inductance 78, while the other end of the series combination is connected to a point intermediate the inductance 78 and the resistor 72. A variable condenser 84 is connected across the inductance 78 and the condenser 82 to form a tunable resonant circuit 86. The common connection of the condensers 80 and 82 is grounded at 88. One side of the filament 64 is connected to a lead 96 of a cable.

A condenser 94 and an inductance 92 are connected in series, and one end of the series combination is connected to the lead 56 of a cable 50 while the other end of the combination is connected to an inductance 90. The inductance 90 is magnetically coupled to an inductance 98, and has one of its ends connected to that inductance to form a coupling unit or intermediate fre-

quency transformer 100. The common connection between the inductances 90 and 98 is grounded at 104. The condenser 102 is connected across the inductance 98 to form a resonant circuit 106. The high potential end of the inductance 98 is connected to a control electrode 108 of a thermionic tube 110. A cathode 112 of the thermionic tube 110 is connected to ground at 104 through a resistor 114. The condenser 116 connected across the resistor 114 forms a bypass circuit for high frequency currents from the cathode 112. An anode or output electrode 118 of the thermionic tube 110 is connected to a lead 120 through which it may be connected to the input of succeeding similar stages, or of a detector.

A primary inductance 126 of a transformer 125 having leads 122 and 124 adapted for connection to the output of a detector, is magnetically coupled to secondary inductances 128 and 130. The inductance 130 is connected to the inductance 128 and forms a part of the complete secondary, and the connection between the inductances provides a mid-tap to which an end of a resistor 132 is connected. The other end of the resistor 132 is connected to a point intermediate choke 134 and resistor 136 which are connected in series and are in series with the lead 96. The extremities of the secondary formed by the series combination of the inductances 128 and 130 are connected to control electrodes 138 and 140 of the thermionic tubes 142 and 144 respectively. Filaments 146 and 148 of the thermionic tubes 142 and 144 respectively, are connected in parallel, and an impedance 150 having a mid-tap 152 is connected across that parallel combination. An end of the resistor 136 is connected to the mid-tap 152 of the impedance 150. Anodes or output electrodes 154 and 156 of the thermionic tubes 142 and 144 are provided with leads 158 and 160 respectively, for connection to an output transformer or other suitable output circuit.

When signals are picked up by the antenna 1, they are applied to the input or control electrode 18 through the coupling device 12. The tuning of the resonant circuit 25 by the variable condenser 16 serves as a selective means to select the desired incoming signals. At the same time the incoming signals are being applied to the control electrode 18 of the detector tube 20, locally generated oscillations are picked up by the inductance 62 by virtue of its magnetic coupling with the inductance 78, and are applied to the filament or cathode element 22 of the detector tube 20 through the condenser 58. The tuning of the variable condenser 84 determines the resonant frequency of the resonant circuit 86 and the frequency of oscillation of the oscillator tube 66. By applying the incoming signals to the control electrode 18 of the tube 20 and the locally generated oscillation to the filament 22 of that tube, the signals are mixed with the locally generated oscillation in that tube. The mixed oscillating energy is then applied to the anode or output electrode 26, and thence to the output circuit formed by the inductances 36 and 38, the condenser 48, the resistor 50 and its variable tap 52, and the lead 56. The difference in frequency between that of the signals applied to the control electrode 18 of the detector 20 and that of the oscillator 66 determines the frequency of the oscillating energy applied to the output electrode 26. Hence, if the condensers 16 and 84 are properly aligned

and tuned in unison, the frequency of the output energy may be kept constant regardless of the frequency of the signal being received.

The biasing potential for the detector tube 20 is applied between the control electrode 18 and filament 22 by virtue of the D. C. potential drop across the choke 44 and resistor 46. The choke 44 has a high reactance to high frequencies and fairly low D. C. resistance so that it tends to prevent the oscillating energy applied to the filament from being by-passed to ground at 2 through the resistor 46. The condenser 58 is large enough to permit the oscillating energy from the oscillation generator to be applied to the filament 22, but prevents the biasing potential between the filament 22 and control electrode 18 from being short circuited through the inductance 62.

The resistor 76 connected between the control electrode 74 and the filament 64 of the oscillator tube 66 forms a grid leak. The inductance 78 connected to the anode 68 and in series with that anode and its source of potential, and magnetically coupled with the inductance 78, provides an inductive feed-back to cause the oscillator tube 66 to oscillate. The resistor 36 connected between the lead 34 and ground at 32, and having a tap 28 serves as a voltage divider, so that the voltage applied to the screen grid 24 of the detector 20 is substantially that of the tap 28, and a voltage applied to the anode 68 is equal to that of the tap 28 minus the voltage drop across the resistor 72 and the inductance 78.

The resistor 50 connected to ground at 54 and to the output circuit intermediate the inductances 36 and 38 through the condenser 48, and having a variable tap 52 connected to the lead 56 serves as a variable voltage divider to determine the voltage applied to the input of the amplifying stages. The condenser 48 permits the oscillating output voltage to pass, but isolates the D. C. potential of the anode 26 from ground at 54 and also prevents that potential from being applied to the amplifier. The voltage thus predetermined by the portion of the resistor 50 between ground at 54 and the variable tap 52 is applied to the primary inductance 90 through the condenser 94 and inductance 92, which condenser and inductance serve to tune the lead 56 to be most efficient at the frequency of the oscillating energy from the detector 20. The secondary resonant circuit 106 is tuned to resonance at the frequency of the oscillating energy applied thereto so that a maximum voltage is applied to the tube 110 between the control electrode 108 and cathode 112. The output energy of the tube 110 from the anode 118 may be applied through the lead 120 to other similar amplifying stages, or to a detector. The biasing potential is applied between the control electrode 108 and the cathode 112 by virtue of the D. C. potential drop across the resistor 114.

After the signals have been amplified and detected they are applied to an audio frequency amplifier through the leads 122 and 124 and the primary inductance 126. The voltage induced into the secondary formed by the inductances 128 and 130 due to the magnetic coupling of the inductance 126, is applied to the control electrodes 138 and 140 of the thermionic tubes 142 and 144. The D. C. potential drop across the resistor 136 provides a biasing potential between the filaments 146 and 148 and the control electrodes 138 and 140. The biasing potential is applied to the control electrodes through the midtap formed by the

connection of the inductances 128 and 130, and through the resistor 132 to permit the signal potential to swing the control electrode potentials either side of the biasing potential, and in a manner such that the signal potentials applied to the control electrodes 138 and 140 will be 180° out of phase. The amplified output signal energy from the anodes 156 and 154 may then be applied to an output transformer or other suitable output circuit through leads 158 and 160 to be reproduced.

The lead 96 connected to the series combination of the filament 64 of the oscillator tube 66 and the filament 22 of the detector tube 20, and to a point intermediate the resistor 132 and the resistor 136 through the choke 134, provides a path through which the anode current of the tubes 142 and 144 will flow to heat the filaments 64 and 22. The anodes 154 and 156 are kept at a positive potential by connecting them, through a choke to the source B. As is well known to those skilled in the art, the direct current blocking condensers are inserted in leads 158 and 156 to the audio output circuit. The circuit may now be traced as follows: From +B to anodes 154, 156 to cathodes 146, 138, choke 150, resistor 136, choke 134, lead 96, cathodes 64, 22, choke 44, resistor 46, ground 2, ground 32, resistor 30 and lead 34. The choke 134 has a high reactance and low resistance, and by virtue of those characteristics permits the direct component of the anode current to flow therethrough without appreciable impedance, but tends to resist the flow of the alternating component of the anode current through the filaments 22 and 64.

The intermediate stage or stages such as that formed by the tube 110 and the coupling device 100 may be especially constructed stages, or may be the radio frequency stages of a conventional 40 tuned radio frequency receiver fixedly tuned to a predetermined frequency, or may be the radio frequency or intermediate frequency stages of a conventional superheterodyne receiver. The audio frequency stage or stages may be those 45 used with anyone of the previously mentioned forms of amplifiers. Then, the lead 34 may be

connected to a suitable point on any of the above mentioned amplifiers from which a satisfactory anode or B potential may be obtained.

The features of this invention are particularly applicable to the type of receiving system disclosed, but might be applied to any type of radio or amplifying device and still come within the scope of the present invention.

While the form of embodiment of the present invention as herein disclosed, constitutes a preferred form, it is to be understood that other forms might be adopted, all coming within the scope of the claim which follows.

What is claimed is as follows:

In a radio circuit the combination including an 15 audio amplifier provided with at least one electronic tube having an anode, a cathode and a control electrode, a frequency changer circuit including an electronic tube provided with an anode, a cathode and a control electrode and an oscillation generator circuit including an electronic tube provided with an anode, a cathode and a control electrode, a connection between the anode and cathode of the first mentioned tube including a source of plate current, a resistor, an inductance 20 coil, the cathode energizing circuits of both said second named tubes and a choke coil all in series, an input circuit for the frequency changer including means for biasing the grid of the tube comprising a connection from the grid electrode 25 of the electronic tube thereof to the cathode thereof including said resistor and inductance coil in series, means for impressing the output of the oscillation generator across said inductance coil and resistor, a source of high frequency 30 energy coupled to the input of the frequency changer circuit, said inductance coil being proportioned with respect to the other elements of the circuit so as to prevent the energy impressed across the inductance coil and resistor from being by-passed by said resistor, said resistor having a comparatively low resistance value.
